(57) **CLAIM**

The ornamental design for a drinking cup, as shown and described.

DESCRIPTION

FIG. 1 is a perspective view of a drinking cup of our design with a base and lid having a drinking spout;

FIG. 2 is a side elevational view of the drinking cup of FIG. 1; FIG. 3 is another side elevational view of the drinking cup of FIG. 1, which is a mirror image of the side elevation view of FIG. 2;

FIG. 4 a top plan view of the drinking cup of FIG. 1;

FIG. 5 is a bottom plan view of the drinking cup of FIG. 1; FIG. 6 is a front elevational view of the drinking cup of FIG. 1;

FIG. 7 is a rear elevational view of the drinking cup of FIG. 1; FIG. 8 is a perspective view of a drinking cup showing our new design with the lid removed for ease of illustration;

FIG. 9 is a rear elevational view of FIG. 8;

FIG. 10 is a front elevational view of FIG. 8;

FIG. 11 is a top plan view of FIG. 8;

FIG. 12 is a bottom plan view of FIG. 8;

FIG. 13 is a side elevational view of FIG. 8;

FIG. 14 is a perspective view of a drinking cup showing our new design with the base removed for ease of illustration;

FIG. 15 is a front elevational view of FIG. 14;

FIG. 16 is a rear elevational view of FIG. 14;

FIG. 17 is a top plan view of FIG. 14;

FIG. 18 is a bottom plan view of FIG. 14; and,

FIG. 19 is a side elevational view of FIG. 14.
